UNITED STATES PATENT OFFICE.

CLARENCE L. BISBEE, OF BROOKLYN, NEW YORK.

GAS-STOVE.

SPECIFICATION forming part of Letters Patent No. 393,094, dated November 20, 1888.

Application filed February 9, 1888. Serial No. 263,644. (No model.)

To all whom it may concern:

Be it known that I, CLARENCE L. BISBEE, of Brooklyn, in the county of Kings and State of New York, have invented a new and Improved Gas-Stove, of which the following is a full, clear, and exact description.

The object of my invention is to provide a very cheap and a very practical gas-stove, which may be regulated to burn practically a small flow as well as a large or full flow of gas; and to these ends the invention consists of the construction and combination, as hereinafter fully described and claimed.

Reference is to be had to the accompanying drawings, forming a part of this specification, in which similar letters of reference indicate corresponding parts in all the figures.

Figure 1 is a vertical sectional elevation of my new and improved gas-burner. Fig. 2 is a plan view of the same. Fig. 3 is a detached plan view of the adjustable device for regulating a small flow of gas. Fig. 4 is a modification of the regulator, and Fig. 5 is a perspective view of the regulator shown in Fig. 3.

A represents the cylindrical chamber, reduced in size at its lower end, as shown at *a*, to fit upon the gas-jet tube B. Openings *b b* are formed in the chamber A to admit air to said chamber, and at the upper end of said chamber is formed the small opening *c*, from which a jet of flame burns when the gas is turned on and lighted. Cast with the chamber A as one casting are the hollow arms C C, the surrounding flange D, and the upright pieces E', which rise from the upper edge of the flange D. In the upper and lower walls of the hollow arms C C are the corresponding passages, *d d'*, formed in casting, so that the whole stove is made in one piece or casting, and is therefore very cheap.

The hollow arms C communicate with the interior of the chamber A, as indicated in Fig. 1, so that when the gas is turned on and lighted it will flow to the ends of the arms C and burn at all of the upper openings, *d*, in the said arms. The air to support combustion at the upper openings, *d*, is supplied through the lower openings, *d'*, so that an intense heat is produced and back-lighting prevented.

When the gas is turned low and a small amount of heat is required, I employ the regulator E, Fig. 5. This is formed with a base or

circular portion, E², having upwardly-projecting plates *f*, as many in number as are arms C. These plates are of such a width as to enable them to enter the apertures *d d'* in the arms C, and they are bent slightly outward, so as to enter the said apertures *d d'* nearest the chamber A. They are also slightly curved inward, so that their upper ends, which are slightly concaved to snugly fit the apertures *d d'*, will impinge against the inner edges of the upper apertures, *d*, leaving a space, *d''*, between the said plates and the inner edges of the lower apertures, as clearly shown at the right in Fig. 1. The object of the plates *f* is to impede the flow of gas so it will not reach to the outer ends of the arms *d*. In the practical application of the regulator E the same is first slipped over the lower end of the chamber A before the same is connected with the stand, and slides upon said chamber, and is attached thereto by the slotted arm *f'*, depending from the circular body E², and a set-screw, *f''*, passing through said slotted arm and entering the side of the chamber A. By this arrangement it will be seen that when the same is not in use it is readily lowered to the position shown in dotted lines, Fig. 1, and also readily elevated to the position for use, as shown in full lines in said figure, and held in place by adjusting the screw *f''*.

The plates *f* of the regulator are slightly concaved and are bent inward, so that the upper ends of the said plates hug the edge of the upper openings, *d*, and leave a space, *d''*, in the lower openings, *d'*, down through which the gas passes. After issuing from the passages *d''*, the gas rises and burns mainly at the angles of and between the hollow arms C C. In this manner a perfect combustion is secured and the jets of flame are confined to a small limit.

In place of the regulator E, placed upon the chamber A, I may use a top regulator, F, (shown in Fig. 4,) to be applied by hand, the plates *h* thereof entering the upper openings, *d*, and projecting down into the lower openings, *d'*, and the said plates *h* diverging, so as to cut the gas off from the upper openings, *d*, but leave the space *d''* in the lower opening, thus effecting the same purpose as the regulator E.

The jet-tube B is shown mounted upon a

small stand, G, to which gas is supplied through a tube, G'.

Having thus described my invention, what I claim as new, and desire to secure by Letters 5 Patent, is—

1. As a new and improved article of manufacture, a gas-stove comprising the chamber A, adapted to fit upon a gas-jet and having opening b near the top of the jet, the radial hollow 10 arms C at the top of the said chamber, and the surrounding flange D, the said hollow arms C being formed with the corresponding openings, d d', at their upper and lower surfaces, substantially as described.

15 2. The combination, with the chamber A, adapted to fit upon a gas-jet, and formed at

its upper end with the hollow arms C, having upper and lower corresponding apertures, d d', of the regulator E, vertically adjustable upon the chamber A, provided with upwardly-extending plates f, adapted to enter the apertures d d' in the arms, their upper ends being slightly concaved and bent inward, whereby said plates will impinge against the inner edges of the upper apertures, d, and leave a space, 20 d', between said plates and the inner edges of the lower apertures, substantially as and for the purpose set forth.

CLARENCE L. BISBEE.
